UNITED STATES PATENT OFFICE.

CHARLES SCHNABEL, OF NEW YORK, N. Y.

DESIGN FOR A CHILD'S MITTEN.

45,653.

Specification for Design.

Patented Apr. 21, 1914.

Application filed January 31, 1914. Serial No. 815,829. Term of patent 14 years.

To all whom it may concern:

Be it known that I, CHARLES SCHNABEL, a citizen of the United States, residing at New York, in the county of New York and State of New York, have invented a new, original, and ornamental Design for a Child's Mitten, of which the following is a specification, reference being had to the accompanying drawing, forming part thereof.

Figure 1 is a front or palm view of the

glove; Fig. 2 is a back view of the glove; and Fig. 3 is a cross section taken through the palm of the glove.

I claim:

The ornamental design for a child's mitten, as shown.

CHARLES SCHNABEL.
